UNITED STATES PATENT OFFICE

HARRISON O. BLAISDELL, OF BROOKLYN, NEW YORK, ASSIGNOR, BY MESNE ASSIGNMENTS, TO ELLIOTT-FISHER COMPANY, OF NEW YORK, N. Y., A CORPORATION OF DELAWARE

COMBINED TYPEWRITING AND COMPUTING MACHINE

Application filed July 3, 1926. Serial No. 120,383.

This invention relates to a combined typewriting and computing machine, and is illustrated as applied to a machine of the Underwood-Hanson type, such as shown in the 5 patents to Hans Hanson, No. 1,278,812, dated September 10, 1918, Ogden Minton, No. 1,280,065, dated September 24, 1918, and others.

Each dial-wheel of each register is associated with a computing bar set by means of the numeral-keys of the typewriter. The computing bars are moved from idle to setting positions in denominational order, by means associated with the carriage of the 15 typewriter; and finally a general operator rotates the dial-wheels in accordance with the numeral-keys which have been depressed.

The machine is automatically set when the carriage moves into predetermined zones, to 20 either add or subtract. The machine has a bichrome ribbon, a red stripe usually indicating subtraction while a black stripe indicates addition. Under certain conditions, especially when typing amounts indicating 25 a debit balance, it may be desired to subtract amounts from the register to clear it and to type the amount in black.

In some systems of bookkeeping in which twin forms are used, the forms are designed 30 so that amounts typed in a column upon one form are additively entered into a register, while the amounts typed in a corresponding column of the other form are subtractively entered into the same register. Heretofore, 35 in order to change the machine from addition to subtraction in a certain zone, it was customary to take out one of the tabulating stops and to replace it with a different kind 40 of a stop. In doing this it was easy to misplace the stops in relation to the column of the work-sheet, resulting in shifting the figures in the same column relatively to each other. According to certain features of this 45 invention, there is provided a special stop which can be used either to obtain black addition or black subtraction in the same column. The stop is provided with a swinging plate 50 which can be thrown to either effective or ineffective position without disturbing the

position of the stop, the plate being resiliently held in place by means of a detent.

Other features and advantages will hereinafter appear.

In the accompanying drawings, 55

Figure 1 is a perspective view, showing a tabulating stop having a swinging plate settable in a position to obtain black subtraction, and shows also the mechanism associated therewith. 60

Figure 2 is a similar view, showing the plate swung in its ineffective position, the machine being normally set for black addition. 65

Figure 3 is a diagrammatic view, showing the ribbon-shifting mechanism of an Underwood typewriting machine set for indicating the field of the ribbon for a black subtraction. 70

Figure 4 is a perspective view of the cam-plate associated with the tabulating stop. 75

Figure 5 is a side view of the tabulating stop, showing the cam-plate in its effective black subtraction position in full lines, and in its ineffective or black addition position in dot-and-dash lines. 80

Figure 6 is a cross-sectional view through line 6—6 of Figure 5 on an enlarged scale. 85

The Underwood computing machine is provided with a carriage 10, upon which a platen 11 is revolubly mounted by means of a shaft 12. The platen serves as a means for receiving the blows of type-bars 13, which are operatively connected to character and numeral keys, not shown. At the rear of the carriage there is provided a cross-bar 14 having teeth 15, which serve as a means for locating and locking tabulating stops 16. Said tabulating stops move with the carriage, and serve as a means for arresting the same when tabulating keys, not shown, release the carriage and raise tabulating plungers 17 in the path of the stops, to thereby position the carriage for a predetermined column of the work-sheet. The plungers 17 engage with the lower edge 18 of one of two side plates 19, which enter the teeth 15 and positively locate the stop. 90

Said edge 18 is also effective to automatically trip the motor after having typed a 100 number upon the work-sheet. To this end, the

machine is provided with a lever 20, rockably mounted upon a stud 21, the lever being swung when the edge 18 engages with a one-way pawl 22 carried by the lever. A link 23 is pivotally mounted upon one end of the lever 20 in a manner to draw the link upwardly when the lever is swung. Said link 23 is operatively connected at the other end thereof to a bell-crank 24 pivotally mounted on a shaft 25. The bell-crank is in turn provided with another link 26 pivotally mounted at one end upon the bell-crank, and controlled at the other end by means of a plate 27. The swinging movement of the lever 20 is effective, by 15 means of the linkage hereinbefore described, to draw the link 26 sidewardly, and thereby permit the swinging movement of an arm 28, fast upon a shaft 29, when urged upwardly by a spring 30. Said spring is strong enough 20 to move a slide 31, which engages by means of a pin 32 a rear extension 33 of the arm 28. The lower end of the slide 31 engages one end of a rocker-arm 34, borne by a pivot-pin 35, in a manner to raise the other end thereof, 25 to thereby move therewith a plunger-pin 36, which is withdrawn from the path of a lug 37 carried by a disk 38 mounted on a driving mechanism, not shown, but effective to reciprocate a general operator 39.

30 When the carriage reaches a predetermined position, it is sometimes desirable to automatically shift the computing mechanism to subtraction. This shifting is controlled by means of a tappet preferably in the form of 35 a projecting shoe or cam plate 40, pivotally mounted at one end upon a stud 41, which serves also as a means for holding and spacing the side plates 19. The cam-plate 40 engages a one-way pawl 42, carried by a lever 43 mounted on the stud 21 in a manner to rock the lever and elevate one end thereof, upon which a link 43^a is pivotally mounted. The link 43^a extends downwardly, and is connected at its lowermost end to a bell-crank 44, 40 pivotally mounted upon the shaft 25. Said bell-crank 44 is provided with a link 45, pivotally mounted thereon, which link is withdrawn from under a lever 46 when the bell-crank is swung by the action of the link 43^a. 45 The lever 46 is fast to a cross-shaft 47, which carries fast thereto a pawl 48 designed to engage in a notch 49, and thereby retain a subtraction-setting bar 50 in its normal or ineffective position, as shown in Figure 1. The withdrawal of the link 45 from under the lever 46 has the effect of releasing a spring 46^a, normally held under tension, and thereby rocking the shaft 47. Obviously, when rocking the shaft, the pawl 48 will disengage the 55 notch 49, thereby permitting a spring 51 to retract the bar 50 to its subtracting position. The bar 50 is effective to set the mechanism for subtraction in a manner such as disclosed in said patent to Minton.

60 65 In order that the operative may be aware

of the character of the computation which takes place, there is provided indicating mechanism, which not only indicates whether the amount is to be added or subtracted, but also the color in which the amount will be typed upon the work-sheet. To this end, there are provided two swinging arms 52 and 53, the latter, which indicates the ribbon-field, being fast to a rock-shaft 54. The arm 52 is operatively connected, by means of a link 55 and an arm 56, to a downwardly-extending link 57, which is supported at its lower end by means of a bracket 58. Said link 57 is in line with a plunger 59, slidably mounted in a bracket 60 and carried by an arm 61 fast to a rock-shaft 62, which in turn is connected to the bar 50 by means of a lever 63, which engages a pin 64 on the bar 50. When the bar 50 moves rearwardly, the plunger engages the lower end of the link, 85 thereby swinging the arm 53 to indicate subtraction, as shown in Figure 3.

Normally, when the machine is set for subtraction, a bichrome ribbon 65 is vibrated in its lower field, so that the typing may appear in red, thereby indicating that the amount has been subtracted. The ribbon is automatically set to print in its black or upper field when the machine is reset for addition. In order to control the shifting of the ribbon to correspond with the character of the computation, there are provided mechanism 66 for vibrating the ribbon, and means including an arm 67 and a link 68 for operatively connecting the rock-shaft 54 to the ribbon-vibrating mechanism 66. It will be seen by an inspection of Figure 1 that the plunger 59, when moved upwardly, not only engages the link 57, but also a pendant or link 69, operatively connected to an arm 70 fast to the rock-shaft 54.

Sometimes, especially when typing a debit balance, it is desired to subtract therefrom the amount shown to clear the register, and to print the amount in black, so as to differentiate it from credit balances on the same sheet, which are typed in red. In order to automatically bring about this condition, when the carriage enters a predetermined computing zone, the cam-plate 40 may be made wide enough to permit one side thereof to engage a one-way pawl 71, carried by a lever 72, pivotally mounted upon the stud 21. This will swing the lever 72 in a manner to draw on a link 73, pivotally mounted thereon, and thereby, by means of an arm 74, swing a shaft 75, which carries fast thereto a second arm 76. The latter is operatively connected to the pendant 69 by means of a link 77, to thereby swing the same out of the path of the plunger 59. By means of this arrangement, the pendant 69 may be rendered ineffective at will, thereby preventing the shifting of the ribbon, although the machine is set for subtraction.

The two thin side plates 19 of the tappet are spaced apart by shouldered studs, as 41 and 82, the ends of the studs being upset on the outside of the plates to bind the plates 5 against the shoulders of the studs in a well-known manner. For the purpose of the present invention, one of the studs, as 41, may have an intermediate shoulder formed by a reduced bearing-surface 85 which enters a 10 hole 86 in an arm 87 formed by bending over one end of the cam-plate 40 at right angles. The arm 87 may be assembled upon the rivet 41 during the assembly of the plates 19 and provide for a free swinging movement of the 15 cam-plate 40 confined between the inner face of one side plate 19 and the shoulder of the rivet.

As it is desirable that the cam-plate 40 shall be semi-locked in the operative position of 20 Figure 1, and also held in the inoperative position of Figure 2, the arm 87 may be provided with a stud 81 permanently riveted to the inner face of said arm to stand parallel to the plane of the cam-plate 40. The stud 25 may have a central blind hole to enclose a compression spring 80 and a detent-ball 78, the edges of the hole after the assembly of spring and ball therein being slightly upset to retain the ball as a pre-assembled unit before the plate 40 is assembled upon the rivet 41. The assembly of the plate 40 upon the 30 rivet 41 compresses the spring 80 by forcing the assembled ball 78 into the stud 81, said ball thereafter being under tension against 35 the inner face of the adjacent side plate 19.

To coact with the ball 78, the adjacent plate 19 may have two holes 79 radial with the rivet 41 and at positions to time the location of the ball 78 for the two positions of the cam-plate 40 in Figures 1 and 2, the inner edges of the 40 holes 79 being chamfered to form suitable cam-plate-holding seats for the ball.

To co-operate with the ball 78 and prevent overthrow of the plate 40 at the end of either 45 of its two manually shifted positions, the arm 87 is formed to strike the rivet 82 in one direction of its swing. To this end, the free end 88 of the arm 87 may be cut away to strike a reduced section 83 of the rivet 82 to align 50 the plate 40 in its computing-control position, and the edge 89 of said plate 40 may strike the larger diameter of the stud 82 in the inoperative stop position of the plate 40, as indicated in broken lines in Figure 5.

55 It will be understood that the cam-plate may be rendered either effective or ineffective by simply swinging it to the positions shown respectively in Figures 1 and 2, and that the cam-plate may be again restored to its former 60 position without necessitating the replacement of the stop. It will be also understood that although the mechanism which reciprocates the general operator will be tripped by engagement with the edge 18 of the plate 19, 65 no harm will result thereby, even though this

particular column of the work-sheet may be a blank column for reasons well known in the art.

Variations may be resorted to within the scope of the invention, and portions of the 70 improvements may be used without others.

Having thus described my invention, I claim:

1. A tappet-unit formed for attachment to a tabulating and computing rack, said unit 75 being a column-stop provided with shiftable means for converting it into a combined column-stop and subtraction-setting stop.

2. A tappet-unit formed for attachment to a tabulating and computing rack, said unit 80 being a column-stop provided with shiftable means for converting it into a combined column-stop and subtraction-setting stop, said tappet-unit including a thin stop-plate engageable within any slot in the tabulating 85 rack to determine a computing-zone position, and a normally inoperative subtraction-setting plate rockably mounted upon the stop-plate to determine a subtractive state for a 90 computing mechanism.

3. A tappet-unit formed for attachment to a tabulating and computing rack, said unit 95 being a column-stop provided with shiftable means for converting it into a combined column-stop and subtraction-setting stop, said tappet-unit including a pair of thin side 100 plates spaced apart by rivets, so that the plates may enter adjacent slots of the tabulating rack to establish a computing zone, and a normally inoperative subtraction-setting plate rockably mounted between the 105 plates upon one rivet and formed with an arm to engage another rivet for a stop-setting position, effective to change a normal state of a computing mechanism to a subtractive state.

4. A tappet-unit formed for attachment to a tabulating and computing rack, said unit 110 being a column-stop provided with shiftable means for converting it into a combined column-stop and subtraction-setting stop, said tappet-unit including a pair of thin side 115 plates spaced apart by rivets, so that the plates may enter adjacent slots of the tabulating rack to establish a computing zone, and a subtraction-setting plate rockably mounted upon one spacing rivet and between the plates to engage alternate sides of another spacing rivet to determine a computative state for a 120 computing mechanism.

5. A tappet-unit formed for attachment to a tabulating and computing rack, said unit 125 being a column-stop provided with shiftable means for converting it into a combined column-stop and subtraction-setting stop, said tappet-unit including a pair of thin plates held together by spacing rivets and each plate engageable between spaced-apart teeth of the tabulating rack, and means rockably 130

mounted upon one of the rivets and between the plates, operable at will to be swung between stop positions on the tappet and determine a computative state for a computing mechanism within a column simultaneously predetermined by the tappet.

6. A tappet-unit formed for attachment to a tabulating and computing rack, said unit being a column-stop provided with shiftable means for converting it into a combined column-stop and subtraction-setting stop, said tappet-unit including a pair of thin plates joined together by a pair of spacing rivets to engage adjacent slots in the tabulating rack, and a subtraction-setting plate disposed at right angles to the pair of plates and assembled between them upon one rivet, said subtraction-setting plate in swingably engaging the other rivet in two directions determining the operative and inoperative positions for said subtraction-setting plate relative to a computing mechanism within a computing zone simultaneously established by the tappet.

25 HARRISON O. BLAISDELL.
